UNITED STATES PATENT OFFICE.

WILLIAM C. HIERING, OF NEWARK, NEW JERSEY, ASSIGNEE TO J. E. MERCOTT CO.,
OF NEWARK, NEW JERSEY, A CORPORATION OF DELAWARE.

BAG-FRAME FASTENER.

Application filed July 31, 1924. Serial No. 729,235.

To all whom it may concern:

Be it known that I, WILLIAM C. HIERING, a citizen of the United States, residing at Newark, in the county of Essex and State 5 of New Jersey, have invented new and useful Improvements in Bag-Frame Fasteners, of which the following is a specification.

This invention relates to bag-frame fastening means, particularly to types in which 10 the frame sides may be positively held in closed relation.

An important object of the invention is to provide a simple and efficient fastening for bag frame sides which is positive in 15 operation and not readily liable to premature separation by strains, jolts or contact with other objects during transit.

Another purpose is to produce a fastener which is spring held when in its operative 20 position, requiring the exertion of force to move it into disengaging position, and which adds to the attractive appearance of a bag to which it is applied.

It is a further aim to provide a fastener 25 comprised of few and simple parts, inexpensive to manufacture and adapted to long continuous service.

These and other analogous objects are accomplished by the novel construction and 30 arrangement of parts hereafter described and illustrated in the accompanying drawing, forming a material part of this disclosure, and in which:—

Figure 1 is a perspective view of a fragmentary portion of a conventional type of 35 bag frame shown in closed position by an embodiment of the invention.

Figure 2 is a fragmentary front view of 40 the same, the key being turned into an unlocked position.

Figure 3 is a transverse sectional view taken through the center of the locking device and showing the bag frame sides as held thereby.

Figure 4 is a similar view showing the 45 parts as sprung together during the turning of the key.

In the drawing the bag frame sides are 50 designated respectively by the numerals 10 and 11, these frames being of the usual channel form and connected at their angularly bent ends by hinges as is common.

Rigidly secured to the upper elements of 55 the frame sides are plates 12 and 13, the same being commonly held by prongs 14

and 15 passed through appropriately formed openings in the walls of the channel members and upset or riveted firmly on the inner sides as shown.

These plates, which are die cut from sheet 60 metal, may be given any preferred ornamental profile, one of the plates, 13 having a substantially central perforation 16 and finished flat throughout.

The other plate 12 is die struck to present 65 a concavo-convex, outwardly extending boss 17 having a slot 18 passing through its center and extending equally at both sides into the flat plate, parallel with the base of 70 the plate.

Vertical indentations 19 are formed at right angles with the slot, centrally of the boss, these indentations being flared outwardly at their outer edges as shown.

A key member, generally designated by 75 the numeral 20, is composed of a flat, perforated head 21 blending into a short cylindrical stem 22, passing freely through the center of the boss 17 and having a reduced extension 23 rotatable in the opening 16, the 80 end of the extension passing through a convex spring washer 24 and riveted therein as at 25.

In operation, when the key head 21 is 85 turned into a horizontal position, as shown in Figure 2, the bag frame sides may be readily opened, the head passing freely through the slot 18 in opening or closing the bag, and the head is caused to remain in any position given it by the effect of the 90 spring washer 24, drawing the shoulder of the stem 22 against the inner side of the plate 13.

To lock the bag, after the frame sides are 95 closed, the key is turned, causing the portion 85 of the head 21 adjacent the stem 22 to impinge on the boss at the sides of the indentations 19, springing the sides together, as shown in figure 4, until the key is turned to a fully vertical position, at which time the plates 12 and 13 return to a parallel position, as shown in figures 1 and 3, the head 21 partially entering the indentations 19 and the inherent spring effect of the plates, added to the function of the washer 24 100 holds the parts securely locked until considerable force is applied to turn the key through an angle of ninety degrees.

Although the foregoing is descriptive of 110 the preferred embodiment of the device, it

will be understood that changes in the form and proportion of the parts may be made within the scope of the appended claims and the general exposition of the invention.

5 Having thus described my invention what I claim as new and desire to secure by Letters Patent, is:—

1. A bag lock comprising a pair of frame sides, plates rigid therewith and extending 10 upwardly in parallel position therefrom, one of said plates having a spherically curved lateral extension, and an elongated slot therethrough, a key having a stem rotatably mounted in the mating plate, the head of 15 said key being adapted to pass through the slot, and means for tensionally retaining the key in an adjusted position.
2. A bag lock comprising a pair of frame sides, plates rigid therewith and extending 20 upwardly in parallel position therefrom, one of said plates having a spherically curved lateral extension, and an elongated slot therethrough, a key having a stem rotatably mounted in the mating plate, the head of 25 said key being adapted to pass through the slot, and means for retaining the head of said key when entered therein, said head preventing separation of the frame sides when so positioned.
3. A bag lock comprising a pair of frame 30 sides, plates rigid therewith and extending

upwardly in a parallel position therefrom, a spheroidal protuberance on one of said plates having an elongated slot and transverse indentations, a key rotatable in the 35 other plate, the head of the key being adapted to pass through the slot, said head being suited to engage in the indentations, and a spring retaining means for said key.

4. The combination with a pair of bag 40 frame sides, of an upstanding plate rigidly fixed at its base edge to each of said frame sides, said plates being parallel and in register, an outstanding concavo-convex boss on one of said plates, said boss having an elongated slot extending equally at each end into the plate parallel with its base edge and flaring undulations at right angles with the slot at the center of the boss, a key 45 having a shouldered stem rotatable in the 50 mating plate, a spring washer fixed on the stem to hold the shoulder thereof under tension against the plate, and a head on said key to pass through the slot when in one position and to rest in the indentations 55 when in another position.

This specification signed and witnessed this 22nd day of July, 1924.

WILLIAM C. HIERING.
